UNITED STATES PATENT OFFICE

157,911

GARMENT HANGER

Sydney A. Schwartz, Hollywood, and Jay E. Bass,
Los Angeles, Calif.

Application January 3, 1949, Serial No. 6

Term of patent 3½ years

(Cl. D14—6)

To all whom it may concern:

Be it known that we, Sydney A. Schwartz and Jay E. Bass, citizens of the United States of America, residing respectively in Hollywood and Los Angeles, county of Los Angeles, California, have invented a new, original, and ornamental Design for Garment Hangers, of which the following is a specification, reference being had to the accompanying drawing, forming a part thereof.

Fig. 1 is a side elevational view of a garment hanger showing our new design,

Fig. 2 is a front elevational view of the hanger,
Fig. 3 is a plan view of the hanger, and

Fig. 4 is a rear elevational view of the hanger.
We claim:

The ornamental design for a garment hanger, as shown.

SYDNEY A. SCHWARTZ.
JAY E. BASS.
